TO HOPEDALE MANUFACTURING COMPANY, OF MILFORD, MASSACHUSETTS, A COR-
PORATION OF MASSACHUSETTS.

THREAD-PARTING DEVICE.

1,279,298.

Specification of Letters Patent. Patented Sept. 17, 1918.

Application filed April 23, 1915. Serial No. 23,325.

To all whom it may concern:

Be it known that we, CLARE H. DRAPER and JONAS NORTHROP, citizens of the United States, residing at Hopedale, in the county of Worcester and State of Massachusetts, have invented certain new and useful Improvements in Thread-Parting Devices; and we do hereby declare the following to be a full, clear, and exact description of the invention, such as will enable others skilled in the art to which it appertains to make and use the same.

The present invention relates to an improvement in thread parting mechanism for weft replenishing looms. When the filling on the bobbin, or filling carrier of a weft replenishing loom has been exhausted to a predetermined extent and the bobbin is about to be ejected from the shuttle, the usual practice is to secure or clamp the thread extending from the fell of the cloth to the outgoing bobbin, sever it relatively near the shuttle by means connected with the shuttle feeler and afterward close to the selavage by parting means mounted on or connected with the loom temple. The thread is thereafter allowed to drop into a receptacle provided for the purpose. In the present invention the thread is not positively clamped prior to the severing operation but is received and retained in a retaining device so that the necessity for the usual somewhat complicated thread clamping means is eliminated. The thread parting means often employed consists of two shearing blades, one of which is fixed and the other movable, the device operating upon the principle of the ordinary scissors. A serious detriment to the more successful operation of this type of thread parting means lies in the rapidity with which the cutting edges are worn away, because of the fact that the thread is not held sufficiently taut between the cutting edges but is allowed to slip between the blades in such manner that they have a binding effect rather than a cutting effect upon the thread. In the present invention a thread positioning device is provided and arranged along beside the thread parting means so that the thread will be properly positioned during the thread parting operation whereby the binding effect is eliminated.

and with it the necessity of constantly resharpening the cutters. The object of the present invention, then, is to produce a 5 thread parting mechanism of improved construction, of simplicity of structure and of greatly increased efficiency, and to these ends the invention consists of the mechanism hereinafter described and claimed. 6

In the accompanying drawings illustrating the preferred embodiment of the invention Figure 1 is a side elevation of the hopper and associated parts of a weft replenishing loom showing the application of the 65 thread parting mechanism thereto; Fig. 2 is a side elevation of the parts shown in Fig. 1 just prior to the final step in the operation of the weft replenishing mechanism; Fig. 3 is a side elevation of the thread parting means showing the parts in the position occupied by them during the thread parting operation; Fig. 4 is a plan on the line 4-4 of Fig. 2 showing in dotted lines the 70 position of the filling thread just before it drops in front of the thread retaining device and Fig. 5 is a detail view of the thread 75 retaining device.

In the illustrated embodiment of the invention, the improved thread parting mechanism is shown as mounted upon a feeler controlled weft replenishing loom. The parts of the weft replenishing mechanism necessary for the operation of the thread parting mechanism consists of a hopper 80 10 mounted upon a bracket 11 secured to the breast beam 12; the hopper arm 13 is mounted upon a rock shaft 14 which extends along the front side of the loom and is connected at the other end with 85 the filling feeler mechanism. Mounted upon the transerrer stud 15 is an arm 16 connected by means of the link 17 with the shuttle feeler 18 which is mounted upon a stud 19 secured to the hopper plate 10. When a 90 fresh supply of filling is to be inserted in the shuttle, the hopper arm 13 moves from the position shown in Fig. 1 to the position shown in Fig. 2, drawing with it the arm 16 to which it is connected by means of the 95 spring 20, and thereupon the shuttle feeler is swung rearwardly or toward the left as shown in Fig. 2.

The thread parting means, indicated gen-

erally by the reference character 21, is mounted upon the lay 22 carried by the sword 23. The means for engaging and drawing the filling thread 24 into position 5 to be acted upon by the thread parting means consists of a thread engaging hook 25 carried by the shuttle feeler 18. A thread parter actuating means 26 is mounted upon the breast beam 12; and a thread receiving and 10 retaining device 27 is mounted upon the loom temple 28 secured to the breast beam. The thread parting means comprises a fixed blade 30 secured within a recess in a bracket 31 secured to the front of the lay 22 and a movable blade 32 pivoted on the fixed blade and the bracket 31 at 33. A helical spring 34 (Fig. 4) encircling the pivot 33 tends to maintain the movable blade in open position. The movable blade 32 is adapted to 15 be actuated by the thread parter actuator 26 contacting with the stud 35 projecting laterally from the lower part of the movable thread parter blade 32 upon a forward beat of the lay when the parts are in the position 20 shown in Fig. 2, which is immediately before the insertion of a fresh supply of filling in the shuttle. A thread positioning device is secured to the base 36 of the thread parter supporting bracket 31 by means of the 25 screws 38. The construction of the thread positioning device 37 is such that the movable thread parter blade 32 passes between the thread positioning device 37 and the thread parter supporting bracket 31 during 30 the thread parting operation. The thread positioning device 37 is provided with an edge 39 which extends rearwardly somewhat beyond the cutting edge of the fixed thread parter blade 30 so that when the thread engaging hook 25 engages the filling thread 24 and draws it against the edge 39 of the positioning device 37 the thread will be held in such position as to be acted upon by the thread parter substantially at right angles 35 to its length throughout the thread parting operation thereby insuring a clean cutting action.

The thread parter actuating means 26 is pivoted at 40 upon a bracket 41 secured to 40 the breast beam 12. It will be observed that the thread parter actuator 26 is in the form of a bell crank lever and that its thread-parter actuating end is provided with a condyle-like formation or boss 42 and that the 45 lever is so mounted that when the shuttle feeler 18 moves rearwardly the weight of the boss 42 causes it to drop into such position that the pin or stud 35 on the movable thread parter blade 32 will strike it upon the 50 forward beat of the lay. The operative position of the boss 42 is determined by the engagement of the lug 43 projecting laterally from the thread parter actuator 26 with a stop 44 secured to the bracket 41. The upper end 46 of the thread parter actuator pro-

jects upwardly into the path of travel of the shuttle feeler 18 and, when the shuttle feeler returns to its inoperative position after the operation of the weft replenishing mechanism the lower end of the shuttle feeler engages the head 46 of the thread parter actuator and moves the actuator into inoperative position.

The thread engaging hook 25 is pivoted at 48 upon a hook supporting lever 49, in turn 75 pivoted at 50 upon the shuttle feeler 18. The spring 51, one end of which engages the thread engaging hook 25 and the other end of which engages a lug 52 projecting laterally from the hook supporting lever 49, tends 80 to maintain the heel 53 of the hook 25 against the lug 52. The thread engaging hook 25 is made thus yielding so that after it has swung to the left and has commenced its forward motion, which causes it to engage 85 the shuttle race 54 (which is indicated in dotted line in Fig. 2 just below the shuttle feeler and the thread engaging hook 25) the end of the hook in striking the surface of the shuttle race will yield and follow along 90 the surface of the race so as to engage the filling thread in case it should occupy a low position relatively thereto. The spring 55 which encircles the pivot pin 50 tends to maintain the tail of the hook supporting 95 lever 49 against the lug 56 projecting laterally from the shuttle feeler 18. The lever 49 is provided on its rear edge with a bulging portion 57 which is adapted to be engaged by a bunter 58 secured upon the shuttle box 59. When the shuttle feeler 18 has moved from the position shown in Fig. 1 to the position shown in Fig. 2 just previous to weft replenishment, the bunter 58 upon the next forward beat of the lay will turn 100 the lever 49 on its pivot so as thereby to push the hook 25 toward the breast beam as shown in Fig. 3. During this forward movement of the thread engaging hook 25 the filling thread 24 is drawn against the thread positioning device 37 in a position to be acted upon by the thread parter and also into the slot 60 of the thread receiving and retaining device 27. Upon the return beat of the lay, the hook supporting lever 49 relieved of the 105 pressure of the bunter 58 will swing into its normal position under propulsion of the spring 55.

The thread receiving and retaining device consists of two jaws, an upper jaw 61, and a lower jaw 62, having a slot 60 between them for receiving the filling thread when the thread engaging hook 25 draws the thread toward the breast beam and for retaining or holding the filling thread after it has been severed, out of the path of the lay, so that this loose end may not be caught up and woven into the cloth. This loose end of filling thread is retained in this position until the thread parter 63 connected with the loom 110

temple severs the thread close beside the selvage; and thereupon the thread drops into a receptacle placed below the loom for that purpose.

5 When the filling on the bobbin or filling carrier has been exhausted to a predetermined extent and the filling feeler or other mechanism has operated to swing the hopper arm 13 to the right and, simultaneously therewith, the shuttle feeler 18 to the left, the thread engaging hook 25 is swung into such position that it will be out of the path of the filling thread as the filling thread is carried forward with the lay. Coincident with the arrival of the filling thread 24 at the position shown in dotted line in Fig. 2, the bunter 58 strikes the hook supporting lever 49 and as the lay continues its forward motion the bunter 58 pushes the lever 49 and the thread engaging hook 25 toward the breast beam, the hook 25 meanwhile engaging the filling thread 24 and carrying it forward. The thread in its forward passage enters the slot 60 in the thread receiving and retaining device 27 before it is acted upon by the thread parter. In drawing the thread forward the thread engaging hook 25 draws the thread against the thread positioning device 37 so that by 30 the time the lay reaches the full extent of its forward beat and the pin 35 on the movable thread parter blade 32 strikes the boss 42 on the thread parter actuator 26, which assumes its operative position immediately upon the backward movement of the shuttle feeler, the thread is in position to be cut. Upon the completion of the thread cutting operation which is simultaneous with the arrival of the lay to the extreme of its forward beat, the loose end of the thread falls in front of the thread retaining device where it is held out of the path of the lay until such time as the thread parter on the loom temple acts upon it, after which it drops into 40 its receptacle.

One feature of the present invention contemplates a thread parting mechanism in which the thread parting means is provided with a thread positioning device so arranged with respect to the thread parting means that when the thread extending from the fell to the outgoing bobbin is to be parted, it is drawn into such position as to be held 50 taut between the cutting blades during the thread parting operation. The means for engaging and drawing the thread into this position is mounted upon a part of the weft replenishing mechanism which is moved toward the lay during the weft replenishing 55 operation, so as to bring the thread engaging means behind the thread, so that as the thread engaging means is pushed forward by the lay, the thread will also be carried forward. The thread receiving and retaining device has a construction of such form

that the thread is not positively clamped at any time but is simply retained or held out of the path of the forwardly beating lay until such time as it is parted close to the selvage. It is, therefore, apparent that the invention may be embodied in other forms than that shown in the illustrated embodiment thereof and be within the spirit of the following claims.

Having thus described our invention, what we claim is:

1. A weft replenishing loom having, in combination, weft replenishing mechanism, a thread parter located relatively near the weft replenishing mechanism for severing the outgoing filling end, a thread holding device located adjacent the selvage consisting of a pair of fixed jaws extending laterally from the selvage, and means operating on the replenishing beat-up of the lay for engaging the outgoing filling end and presenting it to the thread parter and simultaneously therewith drawing it between the jaws of the thread holding device.

2. A weft replenishing loom having, in combination, a lay, a breast beam, weft replenishing mechanism, a temple, a temple thread parter, a thread parter located relatively near the weft replenishing mechanism, a thread receiving and retaining device 95 mounted on the temple and located between the temple thread parter and the thread parter located near the weft replenishing mechanism, said receiving and retaining device comprising separated jaws projecting laterally from the temple toward the weft replenishing mechanism, and means for engaging and positively drawing the thread into the slot between said jaws before the thread is severed by the thread parter near 100 the replenishing mechanism.

3. A weft replenishing loom having, in combination, weft replenishing mechanism, a shuttle feeler, a lay, a breast beam, a thread parter mounted on the lay, and means 110 mounted on the breast beam normally held in inoperative position by the shuttle feeler and released to operative position by the operation of the weft replenishing mechanism to actuate the thread parter on a forward beat of the lay.

4. A weft replenishing loom having, in combination, weft replenishing mechanism, a shuttle feeler, a lay, a shuttle, a breast beam, a temple mounted on the breast beam, 120 a thread retaining device provided with a slot mounted on the temple, thread parting means mounted on the lay and thread engaging means mounted on the shuttle feeler adapted on operation of the weft replenishing mechanism to engage the filling thread extending from the fell to the outgoing bobbin and draw it toward the breast beam so as to bring it within the slot in the thread retaining device.

5. A weft replenishing loom having, in combination, weft replenishing mechanism, a lay, a shuttle, a breast beam, a temple mounted on the breast beam, a thread retaining device provided with a slot mounted on the temple, thread parting means mounted on the lay, and thread engaging means connected with the weft replenishing mechanism and adapted on operation of
- 5 10 the weft replenishing mechanism to engage the filling thread extending from the fell to the outgoing bobbin and draw it toward the breast beam so as to bring it within the slot in the thread retaining device.
- 15 6. A weft replenishing loom having, in combination, weft replenishing mechanism, a shuttle feeler, a lay, a breast beam, thread parting means mounted on the lay, including a thread positioning device, and means
- 20 mounted on the shuttle feeler for engaging the thread and drawing it against the thread positioning device.
- 25 7. A weft replenishing loom having, in combination, weft replenishing mechanism, a lay, a breast beam, thread parting means mounted on the lay, including a thread positioning device, and means connected with the weft replenishing mechanism for engaging the thread and drawing it against the
- 30 thread positioning device.
- 35 8. A weft replenishing loom having, in combination, weft replenishing mechanism, a shuttle feeler, a lay, a breast beam, a thread parter mounted on the lay, means mounted on the breast beam for actuating the thread parter upon the operation of the weft replenishing mechanism, and thread engaging means mounted on the shuttle feeler, self-actuated to move into inoperative
- 40 position and having provision for operative actuation during the thread engaging operation.
- 45 9. A weft replenishing loom having, in combination, weft replenishing mechanism, a lay, a breast beam, a thread parter mounted on the lay, means mounted on the breast beam for actuating the thread parter upon the operation of the weft replenishing mechanism, and thread engaging means connected with the weft replenishing mechanism, self-actuated to move into inoperative
- 50 position and having provision for operative actuation during the thread engaging operation.
- 55 10. A weft replenishing loom having, in combination, weft replenishing mechanism, a lay, a breast beam, a shuttle feeler, means mounted on the shuttle feeler for engaging and drawing a filling thread toward the
- 60 breast beam on the operation of the weft replenishing mechanism, and means mounted on the lay for striking and pushing forward toward the breast beam the thread engaging means.
11. A weft replenishing loom having, in combination, weft replenishing mechanism, a lay, a breast beam, means connected with the weft replenishing mechanism for engaging and drawing a filling thread toward the breast beam on the operation of the weft replenishing mechanism, and means mounted on the lay for striking and pushing forward toward the breast beam the thread engaging means.
12. A weft replenishing loom having, in combination, a lay, a thread parter mounted on the lay, a shuttle feeler, a breast beam, thread parter actuating means mounted on the breast beam, said thread parter actuating means being maintained in inoperative position by the shuttle feeler during normal operation of the loom and being adapted to assume an operative position on the backward movement of the shuttle feeler.
13. A weft replenishing loom having, in combination, a lay, a thread parter mounted on the lay, a breast beam, thread parter actuating means mounted on the breast beam, a shuttle feeler, and a thread engaging hook support mounted on the shuttle feeler having a thread engaging hook mounted on the support and movable relatively thereto.
14. A weft replenishing loom having, in combination, weft replenishing mechanism, a lay, thread parting means mounted on the lay including a bracket having a fixed cutting member secured thereto, a movable cutting member pivoted thereon, and a thread positioning device secured thereto, a shuttle feeler, thread engaging means mounted on the shuttle feeler for engaging the thread of an outgoing bobbin upon an operation of the filling replenishing mechanism and drawing it against the fixed cutting member and the positioning device, means mounted on the lay for actuating the thread engaging means, a breast beam, means mounted on the breast beam normally held in inoperative position by the shuttle feeler for actuating the thread parting means a temple secured to the breast beam and a device mounted on the temple provided with means for receiving the thread extending from the fell to the outgoing bobbin as it is drawn toward the lay after it has been engaged by the thread engaging means and for retaining it after the thread parting operation.
15. A weft replenishing loom having, in combination, weft replenishing mechanism, a temple thread cutter, a thread parter located near the shuttle box, a thread retainer located near the selvage for retaining the thread without clamping it until it has been cut by the temple thread cutter, and a thread engager to deliver the thread simultaneously to the parter and to the retainer.
16. A weft replenishing loom having, in

combination, weft replenishing mechanism, a thread parter on the lay near the shuttle box, a temple parter, a thread engaging device for delivering the thread to the two 5 parters.

17. A weft replenishing loom having, in combination, weft replenishing mechanism, a lay, a shuttle box, a thread parter on the lay near the shuttle box, a temple thread 10 parter, and a thread retainer near the temple thread parter and between the latter and the thread parter on the lay, said thread retainer having provision for retaining the thread after it has been severed by the part 15 on the lay and until it is severed by the temple parter.

18. A weft replenishing loom having, in combination, weft replenishing mechanism, a shuttle, a bobbin, a thread parter mounted 20 on the lay having normally open blades, means separate from the blades for positively engaging and drawing the thread of the outgoing bobbin between the blades and means for causing the blades to close 25 upon and cut the thread upon operation of the weft replenishing mechanism.

19. A weft replenishing loom having, in combination, a lay, a shuttle, and a thread parter mounted on the front of the lay having 30 a fixed blade disposed in front of the path of the shuttle and a movable blade normally below the plane of the path of the

shuttle, said blades being and operating outside of the path of the shuttle.

20. A weft replenishing loom having, in combination, a lay including a shuttle race, 35 a thread parter, and a yieldingly mounted thread engaging hook for bringing the thread into position to be acted upon by the parter, constructed and arranged to be 40 swung into a position of clearance with respect to the thread until the thread has been carried forward beyond the engaging end of the hook, and thereafter to be brought in contact with the shuttle race behind the 45 thread and move forward across the shuttle race.

21. A feeler-controlled weft replenishing loom having, in combination, a lay, a thread parter mounted on the lay having two blades 50 normally open in front of the thread, means for drawing the thread into position to be acted upon by the thread parter, and means for actuating the parter.

22. A weft replenishing loom having, in combination, a lay, a shuttle box, a thread parter mounted on the lay and located near the shuttle box, a thread receiving and retaining device located near the selvage, and a thread engaging device having provision 55 for delivering the thread to the thread parter and to the retaining device.
